(57) **CLAIM**

The ornamental design for quick release double flashlight rail mounting system, as shown and described.

DESCRIPTION

FIG. 1 is a right elevation view of the quick release double flashlight rail mounting system thereof, the left side being a mirror image;

FIG. 2 is a top elevation view thereof;

FIG. 3 is a bottom elevation view thereof;

FIG. 4 is a top, front, left side perspective view thereof;

FIG. 5 is a front elevation view, the rear elevation view being a mirror image thereof; and,

FIG. 6 is a top, front, left side perspective view, of FIG. 4, shown attached to a rail and flashlight thereof.

The broken line showing of a rail and flashlight, in FIG. 6, is for illustrative purposes only and forms no part of the claimed design.
